Primary Examiner—B. J. Bullock[57] **CLAIM**

The ornamental design for a clamping mould used in order to make deep frozen foods, as shown and described.

DESCRIPTION

FIG. 1 is a front elevational view of a clamping mould used in order to make deep frozen foods showing my new design;
FIG. 2 is a left end elevational view of said mould;
FIG. 3 is a right end elevational view of said mould;
FIG. 4 is a rear elevational view of said mould;
FIG. 5 is a top plan view of said mould;
FIG. 6 is a bottom plan view of said mould; and.
FIG. 7 is an enlarged fragmentary perspective view of said mould.
